FIG. 5.

UNITED STATES PATENT OFFICE

FLOYD F. KISHLINE, OF DETROIT, MICHIGAN, ASSIGNOR TO GRAHAM-PAIGE MOTORS CORPORATION, A CORPORATION OF MICHIGAN

MANIFOLD HEAT CONTROL

Application filed August 7, 1930. Serial No. 473,705.

This invention relates to manifold heat control devices.

The main objects of this invention are to provide an improved heat control device for 5 directing exhaust gases into contact with the intake manifold and then automatically terminating the flow of gases upon a rise in temperature within the intake manifold; to provide an improved construction in combination 10 with a mixture enriching device such as a carburetor choke valve, in which the exhaust gases are directed into contact with the intake manifold when the mixture of the carburetor is enriched; and to provide an improved 15 type of two stage control whereby all of the exhaust gases are directed into contact with the intake manifold when the motor is cold and a portion only of the gases directed into contact with the intake manifold when 20 the motor has warmed up to a certain predetermined point, and to terminate the flow of exhaust gases to the intake manifold when the temperature of the motor further rises to another predetermined point.

25 An illustrative embodiment of this invention is shown in the accompanying drawings, in which

Fig. 1 is a view in elevation of an internal combustion motor intake and exhaust manifolds and carburetor therefor with my improved heat control mechanism adapted thereto.

Fig. 2 is an enlarged sectional view showing the thermo-responsive unit and locking mechanism operated thereby, the view being taken on the line 2—2 of Fig. 1, looking in the direction indicated.

Fig. 3 is a fragmentary sectional view taken on the line 3—3 of Fig. 4 looking in the direction indicated.

Fig. 4 is an enlarged vertical longitudinal sectional view taken through the medial part of the heat control apparatus with fragmentary parts shown in sectional detail.

Fig. 5 is an enlarged sectional view taken on the line 5—5 of Fig. 1, looking in the direction indicated, showing the exhaust gas directing valve in closed position in full lines and in open and partially open position in dotted lines.

In my improved heat control apparatus the intake and exhaust manifolds of an internal combustion motor are connected together at their medial points where the carburetor riser passes into the intake manifold. 55 The manifolds are so designed and arranged as to provide a passageway leading from the exhaust manifold to the walls of the intake manifold and a valve is arranged in this passageway, which, when in open position, will 60 cause all of the exhaust gases to pass around and in contact with the intake manifold, and when in closed position will terminate such flow of exhaust gases.

The valve for controlling the exhaust gases 65 is normally urged to a closed position by a suitable torsion spring and connections are provided between the valve and a carburetor mixture enriching device so that when the mixture is enriched the valve will be moved to 70 an open position and releasably locked in such position.

Thermo-responsive means are provided for releasing the lock upon a predetermined rise 75 of temperature within the intake manifold. The arrangement, however, is such that the valve is closed in a two-stage operation, that is, when it is first released from a full open position it will be moved to a partially open position, preferably half open and releasably 80 secured at that point. Upon a further rise in temperature within the intake manifold the locking means will again be released so as to permit the torsion spring to fully close 85 the valve.

In the construction shown in the drawings an intake manifold 6 and exhaust manifold 7 are joined together at their medial points immediately above the riser 8 of a carburetor 9. The exhaust manifold 7 comprises the usual header 10 and branches 11 which conduct the exhaust gases from both ends of the internal combustion motor 12 toward the middle, at which point the gases normally pass from the header 10 directly to an exhaust pipe 13, as shown by the arrow 14 in Fig. 5.

The exhaust manifold, at this middle point, is provided with a passageway 15 which leads to and communicates with a passageway 16 which passes down around one side of the 100

intake manifold 6 and communicates with horizontally disposed passageways 17 formed at each side of the riser 8. The passageways 17 communicate with a passageway 18 at the 5 opposite side of the intake manifold which in turn communicates with a passageway 19 formed in the exhaust manifold and which leads to the exhaust pipe 13. An upwardly extending fin or partition 20 is integrally formed on the top side of the manifold 6 which is in registry with a continuing portion 10 21 of the exhaust manifold.

A valve in the form of an elongated rectangular relatively flat body 22 is provided 15 with trunnions 23 and 24 integrally formed on opposite ends thereof which are journaled in bearings formed in end walls 25 and 26, respectively. Inner and outer side walls 27 and 28 are provided which together with the 20 end walls form the passageway leading down and around the intake manifold.

The details of construction of this valve and mounting means therefor are described and shown in detail in my co-pending application Serial Number 473,706, filed 25 August 7, 1930.

The trunnion 23 is connected by a collar 29 to a co-axially extending shaft 30, the opposite end of which is connected by a collar 31 to the protruding end 32 of a shaft 33 of a 30 thermo-responsive unit.

Yielding means is provided for normally urging the valve 22 to a closed position as shown in full lines in Fig. 5 of the drawings 35 and comprises a helical torsion spring 34 which surrounds the collar 31. One end of the spring 34 is anchored to a flange 35 rigidly secured to the shaft 30 by a pin 36, and the other end of the spring is turned outwardly 40 to engage back of a lug 37 which is struck out from the end wall 38 of the casing which surrounds the thermo-responsive unit. A plurality of lugs 37 are provided in circumferentially spaced position so that the tension 45 on the spring 34 may be varied to suit the conditions and circumstances as required.

The shaft 33 carries a segment 39 rigidly secured thereto by a pin 40. The outer periphery of the segment 39 is provided with 50 a pair of radially extending angularly spaced lugs 41 and 42, the lug 42 being longer than the lug 41 so as to be spaced a further distance from the axial center of the shaft 33.

Means are provided for engaging the lugs 55 41 and 42 so as to releasably lock the shaft 33 and comprises a depending hook 43 integrally formed at the outer end of an arm 44 which is pinned to a shaft 45. The opposite ends of the shaft 45 protrude from the sides of the 60 arm 44 and are journaled in axially registering apertures formed in the end wall 38 and a sub-wall 46.

The depending hook 43 is positioned in the path of travel of the lugs 41 and 42 so as to 65 normally engage back of said lugs when the

segment is rotated in a left hand direction as viewed in Fig. 2 of the drawings. The segment 39 is also provided with a radially extending arm 47 which abuts against the inner end of an adjusting screw 48 fitted in the front wall 49 of the housing which surrounds the thermo-responsive unit. A lock nut 50 is provided on the adjusting screw 48 for securing it in adjusted position, the screw 48 being arranged so as to position the valve 22 in fully closed position when rotated by the torsion spring 34.

Means are provided for releasing the hook 43 from engagement with the lug 41 and comprises a thermo-responsive element such as a bellows 51, which is mounted partially within the intake manifold 6 so as to be controlled by the temperature within said intake manifold. The bellows 51 is connected through a suitable rod 52 to the outer end 53 of arm 44 so that expansion of the bellows will move the rod 52 upwardly and raise the hook 43 sufficiently to release it from the lugs 41 and 42.

Means are provided for manually moving the valve 22 to an open position and comprises a rod 54, one end of which terminates at the vehicle dash, and the other end of which is connected to an arm 55 secured to the shaft 30. A link 56 connects the arm 55 with an arm 57 which controls the mixture enriching device 55 of the carburetor 9.

Such mixture enriching device may be the well known choke valve or other type of more modern enriching device in which a supplemental supply of gasoline is introduced into the carburetor for the purpose of starting the motor when cold.

In the operation of this device suitable tension is placed on the spring 34 to rotate the valve 22 toward a closed position. The screw 48 is adjusted so as to position the valve 22 in fully closed position as shown in full lines in Fig. 5 of the drawings. When the motor is cold it is a universal custom to pull out on the dash control for closing the choke valve or actuating some other form of mixture enriching device.

Such manual operation of the rod 54 will not only actuate the mixture enriching device through the link 56 and 57, but will also rotate the shaft 30 so as to move the segment 39 in a left-hand direction until the lug 41 is engaged back of the hook 43, at which point it is releasably locked against the action of the torsion spring.

When in this position, the valve 22 is in full open position, thus causing all of the exhaust gases from the header 10 of the exhaust manifold to pass down through the passageways 15 and 16, underneath the intake manifold through the passageways 17 which are at each side of the riser 8, upwardly through the passageways 18 and 19, and thence out through the exhaust pipe 13.

Passage of the exhaust gases around the

intake manifold will quickly heat the manifold at the point where it joins the riser so as to raise the temperature of the incoming gases from the carburetor, which rise in temperature will facilitate their combustion within the internal combustion motor.

When the temperature of the incoming fuel mixture has been raised to a predetermined degree, the thermostatic bellows 51 will expand sufficiently to release the hook 43 from engagement behind the lug 41, at which time the torsion spring 34 will rotate the shafts 30 and 33, valve 22, and segment 39 in a right-hand direction, as viewed in Fig. 2 of the drawings, until the lug 42 comes in contact with the hook 43.

As hereinbefore pointed out, the lug 42 is spaced a greater distance from the axial center of the shaft 33 than the lug 41 and will thus engage the hook 43 after said hook has been lifted a distance sufficient to release it from engagement with the lug 41. When the hook 43 engages the lug 42, the valve 22 will be in partially closed position as shown in dotted outline in Fig. 5, thus directing part of the exhaust gases down around the intake manifold and permitting the remainder thereof to pass directly out through the exhaust pipe 13.

When the temperature of the intake mixture is further raised to a predetermined degree, the bellows 51 will be further expanded sufficiently to disengage the hook 43 from the lug 42. Such release permits the torsion spring 34 to further rotate the shaft 30 and valve 22 until the arm 47 comes in contact with the end of the adjusting screw 48, at which time the valve 22 will be in fully closed position as shown in full lines in Fig. 5 of the drawings.

Under certain conditions such as extremely cold weather, the valve 22 may remain in partially closed position or even in full open position, depending upon the temperature of the fuel mixture.

Although but one specific embodiment of this invention has been herein shown and described, it will be understood that numerous details of the construction shown may be altered or omitted without departing from the spirit of this invention as defined by the following claims.

What I claim is:

1. In an internal combustion motor, the combination of an intake manifold, an exhaust manifold having a passageway leading to a wall of said intake manifold, a valve for controlling the passage of exhaust gases through said passageway, manually operable means for moving said valve to an open position for directing exhaust gases into contact with said intake manifold, yielding means normally urging said valve to a closed position, locking means for releasably securing said valve in open position, thermo-responsive

means for releasing said locking means, and means for releasably securing said valve in a partially closed position, said thermo-responsive means being adapted to release said locking means at partially closed position so as to permit said yielding means to fully close said valve.

2. In an internal combustion motor, the combination of an intake manifold, an exhaust manifold having a passageway leading to a wall of said intake manifold, a valve for controlling the passage of exhaust gases through said passageway, manually operable means for moving said valve to an open position for directing exhaust gases into contact with said intake manifold, yielding means normally urging said valve to a closed position, locking means for releasably securing said valve in open position, means responsive to the temperature in said intake manifold for releasing said locking means, and means for releasably securing said valve in a partially closed position, said thermo-responsive means being adapted to release said locking means at partially closed position so as to permit said yielding means to fully close said valve.
